UNITED STATES PATENT OFFICE.

DAVID T. FOLEY, OF CHICAGO, ILLINOIS.

DESIGN FOR A SPOON.

SPECIFICATION forming part of Design No. 21,266, dated December 29, 1891.

Application filed September 7, 1891. Serial No. 405,032. Term of patent 3½ years.

To all whom it may concern:

Be it known that I, DAVID T. FOLEY, a citizen of the United States, residing at Chicago, county of Cook, and State of Illinois, have invented and produced a new and original Design for Spoons, of which the following is a specification.

My invention relates to designs for spoons, particularly such as will be appropriate for use in connection with or as suggestive of the World's Columbian Exposition of 1893.

The chief feature of my design is the group upon the spoon of the arms of the United States of America, with the flag of the United States, and the building of the United States at the World's Columbian Exposition of 1893. This is illustrated in the accompanying drawing, in which—

A is the bowl of the spoon, B the handle, and C the tip of the handle.

My design is arranged substantially as follows: Upon the tip C of the handle is the representation of the arms of the United States of America, while entwined about the handle B is the United States flag, and in the bowl A of the spoon is the building of the United States at the exposition.

Words and lettering descriptive of the design may be placed upon the spoon or omitted, as desired, as such letters form no essential feature of my design.

I have referred to the flag as entwined about the handle of the spoon. This is as it appears in the face view. The reverse of the spoon may be plain, if desired.

I claim as new and desire to secure by Letters Patent—

The design for spoons, substantially as herein shown and described.

DAVID T. FOLEY.
